UNITED STATES PATENT OFFICE.

GEORGE H. HARLOW, OF HUDSON, MASSACHUSETTS, ASSIGNOR TO HARLOW SHOE FINISHING MACHINERY COMPANY, OF BOSTON, MASSACHUSETTS, A CORPORATION OF MASSACHUSETTS.

APPARATUS FOR APPLYING WAX TO BOOTS AND SHOES AND THE LIKE.

No. 868,923.

Specification of Letters Patent.

Patented Oct. 22, 1907.

Application filed August 7, 1905, Serial No. 273,066. Renewed June 25, 1907. Serial No. 380,752.

To all whom it may concern:

Be it known that I, GEORGE H. HARLOW, a citizen of the United States, residing at Hudson, in the county of Middlesex and State of Massachusetts, have invented an Improvement in Apparatus for Applying Wax to Boots and Shoes and the Like, of which the following description, in connection with the accompanying drawing, is a specification, like letters on the drawings representing like parts.

10 This invention has for its object the production of novel apparatus for applying wax on the heels and other parts of boots and shoes and the like, as the same are being finished.

I have illustrated my invention as adapted to applying wax to a rotatable member that lays the wax on a heel edge.

My improved apparatus embodies a rotary textile-covered member and a wax distributor shown as a block of metal, preferably concaved at its face that contacts 20 with the rotatable member, said distributor having a series of ducts, through which the melted wax is forced by said member as the latter is rotated, the friction of the rotatable member against the distributor heating both the cover of the rotatable member and the distributor sufficiently to keep the wax in a semi-liquid condition.

The wax will preferably be first applied to the under side of the rotatable member, and portions of the wax melted by contact with said member will be carried 30 upwardly between said member and the concaved face of the distributor, the wax entering the lower ends of the ducts of the distributor, and being delivered at the upper end thereof through the distributor being inclined downwardly toward the axis of rotation of said rotatable member.

Figure 1 in front elevation illustrates an apparatus embodying my invention; Fig. 2 a view of part of the apparatus to the left of the dotted line x; Fig. 3 is a view enlarged of the inner face of the distributor, and Fig. 4 40 shows the distributor in vertical section, the dotted lines showing part of the rotatable member.

The standard A has suitable uprights or bearings that sustain two shafts, A', A'', each provided with a belt-pulley, as A³, A⁴, about which, in practice will be extended belts driven from pulleys A⁵, A⁶ on a power shaft A⁷ sustained in the standard. The shaft A' has secured to it the hub of a disk or wheel a preferably of wood, and having a textile covering composed of a layer of felt a' and a cover a'' of cloth, preferably cotton. The 50 covering is therefore non-metallic, is yielding, and as shown is of textile material, and the wheel and its yielding covering constitute what I designate as the rotatable member.

The distributor B comprises a steel block, having a concave face b and an inclined top b', and the face of the distributor is provided with one or a series of ducts b² that, as shown, lead from near the center of the length of the distributor to its top. The top of the distributor has side walls 2 that co-act with the top b' to form a wax-holding chamber, and the side of the distributor is also shown as having flanges 3 to embrace the sides of the rotatable member.

The distributor is carried by a spring C pivoted at 6 to part of the framework or a standard A, and by turning two nuts 7, 8 on a screw-rod C' attached to the spring and extended loosely through the rigid standard, the pressure and consequently the degree of friction between the rotatable member and the face of the distributor may be determined. The greater the pressure and the higher the speed of the rotatable member, the hotter the surface of the rotatable member and the distributor.

When the machine has been run long enough to heat the rotatable member and distributor sufficiently to melt the wax used for finishing the exterior of a heel of a boot or shoe, the operator holds the wax in its cold state against the periphery of the wheel, and the periphery being heated takes the wax and carries it up against the face of the distributor, and the melted wax is forced by the wheel into the lower ends of the ducts, and is delivered from the upper ends of said ducts on the incline of top b' of the distributor, and resting on the incline is taken therefrom by the periphery of the rotatable member and applied to the heel, or other part of a boot or shoe which is held in contact with said member. The side walls 2 of the distributor extended above the inclined top part serve to retain the melted wax until taken up by the periphery of the rotatable member as the latter is rotated rapidly.

The shaft A² is shown as provided at one end with a brush E that may be employed to act against the heel edge coated with wax by the parts described, said brush acting to give a polish to the waxed surface.

Having fully described my invention, what I claim as new and desire to secure by Letters Patent is:

1. In apparatus of the class described, a rotatable member, combined with a distributor in engagement with said rotatable member and provided with ducts leading to the upper end of said distributor.

2. In apparatus of the class described, a rotatable member, combined with a distributor concaved at its face and provided with ducts leading to the upper end of said distributor.

3. In apparatus of the class described, a rotatable member having a non-metallic covering, combined with a distributor concaved at its face and provided with ducts leading to the upper end of said distributor.

4. In apparatus of the class described, a rotatable

- member, combined with a distributor having its upper end inclined toward the center of rotation of said member and concaved at its face and provided with a series of ducts leading to the upper end of said distributor.
5. In apparatus of the class described, a rotatable member, combined with a distributor concaved at its face and provided with ducts leading to the upper end of said distributor, and means to regulate the pressure of said distributor against said rotatable member.
10. 6. A wax distributor comprising a metal block concaved at its face and having an inclined top provided with walls, the face of said block being provided with ducts leading from said face upwardly to the top of the block through which heated wax may be forced to the top of the block.
7. In apparatus of the class described, a metallic distributor, a rotatable member, means to hold said rotatable member pressed against said distributor, and means to rotate said member, the friction generated by the contact of the member with the distributor heating the distributor and member and melting the wax that the rotatable member may apply the same to the surface to be waxed. 15
20

In testimony whereof, I have signed my name to this specification, in the presence of two subscribing witnesses.

GEORGE H. HARLOW.
